STENOGRAPHIC MACHINE

Waldemar A. Ayres, Flushing, N. Y., assignor to
 International Business Machines Corporation,
 New York, N. Y., a corporation of New York

Application October 21, 1944, Serial No. 559,777

7 Claims. (Cl. 197—9)

1

The present invention relates to improvements in stenographic recording devices and more particularly to an improved key arrangement and mechanism controlled thereby for perforating or printing a record strip at high speed.

The improved key arrangement and printing mechanism controlled thereby which comprises the present invention has been shown and described in connection with stenographic machines having keyboards of the type illustrated in my prior patent, No. 2,189,023, dated February 6, 1940, for a Punching and printing device. Such an apparatus relates to machines of the class intended particularly for the rapid recording of speech by the individual or simultaneous manipulation of keys. The object accomplished by such machines is to enable the operator, according to spelling, to write at one stroke an entire word or as much of the word as is possible. The keys, when simultaneously depressed, produce a sequence of letters on the record and the record is moved one step after each stroke in readiness for a new series of letters to be produced by the next stroke.

In machines of this type, extreme rapidity and facility in the manipulation of the keys is attained. Furthermore, the keyboard arrangement is such that it will permit recording of the greatest number of complete words or phrases, or syllables of the word, as the case may be, at one stroke with a minimum number of key depressions and with the minimum demand for digital dexterity.

The invention disclosed herein relates, in one phase thereof, to a new type bar action which depends for its functioning upon proper manipulation of a keyboard of the type shown in my above mentioned patent. Each type bar carries a plurality of type elements and the type bar itself is selectively shiftable with respect to the printing point on the platen under the control of one or more keys at the keyboard. Depending upon the particular key or keys depressed at the keyboard, the type bar under the control thereof is caused to become tilted so that a selected type becomes aligned with the platen prior to movement of the type bar in a direct line into engagement with the platen. The type bar action includes a toggle mechanism which is moved in a substantially straight line at the time of the printing operation, such straight-line movement of the type bar being attained regardless of the inclination of the bar or of the particular type carried thereby which at the time of printing is in register with the platen.

Accordingly, among the principal objects of the invention, in a machine of the character set forth above, is the provision of keyboard controlled means for moving type bars into engagement with

2

a platen, the type bars being carried on swinging shiftable arms or supports whereby they move bodily to and from the platen in substantially straight lines, while at the same time means are provided for shifting the relative position of the type bars with respect to the platen prior to their final straight-line movement.

Another object of the invention is to provide a type bar actuating means under the control of one or more keys of the keyboard for tilting the type bars to align a selected character thereon with the printing point on the platen.

A further object of the invention is to provide a control means for type bars having a plurality of type thereon and in which the bars operate under the control of a keyboard, one or more keys of which serve to control the means for tilting the type bar to print from a selected type, interlocking means being provided between the various keys for preventing shifting of a type bar after one or more of the keys which control it have been fully depressed.

The type bar action of the present invention is of the so-called portable noiseless type in which 25 the swinging type bars are arranged radially with respect to the printing point on the platen. Heretofore, in most instances, each of the portable type bars has been provided with only two types so that the number of type bars equals the number of 30 keys. A few other machines of this type employ four types upon each type bar which are operable by either of two keys, thus reducing the number of noiseless pivoted type bars to half the number of keys in order to compact the type bar system. 35 It is a feature of the present invention to provide each noiseless swinging type bar with five types to be operable by one or more of a group of three keys, thus still further reducing the number of pivoted type bars and greatly simplifying and 40 compacting the type bar system.

According to the present invention, single operation of each key in a group of three serves to selectively tilt the type bar to permit a selected type to register with the platen. Depression of 45 one pair of adjacent keys simultaneously serves to further tilt the type bar to present a fourth type to the platen. Similarly, simultaneous depression of another pair of adjacent keys in the group serves to tilt the type bar so that the fifth type carried thereby will be presented to the platen. Such control of five different types on a single type bar by means of only three keys in the keyboard is effected without destroying the ability of the types to move in paths which are at 50 right angles to the platen, or nearly so, this latter feature being conducive to good typing impressions.

The system of writing developed in accordance with the present stenographic machine is based upon discoveries and principles fully set forth

and claimed in my prior patent mentioned above. The present invention is concerned primarily with the mechanical structure of the type bars and of the actuating means therefor.

The present invention is also concerned with a novel type of ribbon feeding and reversing mechanism and, accordingly, a further object of the invention is to provide a simplified form of ribbon feeding mechanism embodying automatically operable ribbon reversing features.

Likewise, the present invention, in another form thereof, is concerned with a novel form of platen indexing or advancing mechanism operable at each depression of a key or keys of the keyboard to index the platen and advance the tape one step or line space through the machine.

Numerous other objects and advantages of the invention not at this time enumerated will become apparent as the following description ensues.

In the accompanying six sheets of drawings forming a part of this specification, one embodiment of the invention is shown. In these drawings:

Fig. 1 is a top plan view of a stenographic machine constructed in accordance with the principles of the present invention.

Fig. 2 is a side elevational view of the machine shown in Fig. 1.

Fig. 3 is a detailed, top plan view of the machine with the cover plate thereof removed. In this view, certain of the keys comprising the keyboard have been removed and their presence indicated in dotted lines to more clearly illustrate the nature of the invention.

Fig. 4 is a fragmentary, top plan view of a localized region of the machine.

Fig. 5 is an enlarged, detailed, side elevational view, partly diagrammatic in its representation, showing one of the type bars operatively associated with its operating instrumentalities whereby it is selectively operated from the keyboard.

Fig. 6 is a sectional view taken substantially along the line 6—6 of Fig. 5.

Fig. 7 is a fragmentary, schematic view illustrating the action of a series of permutation bars and key levers employed in connection with the present invention.

Fig. 8 is a sectional view taken substantially along the line 8—8 of Fig. 3.

Fig. 9 is a sectional view taken substantially along the line 9—9 of Fig. 3. In this view, certain parts have been omitted to more clearly reveal the nature of the invention.

Fig. 10 is a sectional view taken substantially along the line 10—10 of Fig. 9.

Fig. 11 is a sectional view taken substantially along the line 11—11 of Fig. 9.

Fig. 12 is a sectional view taken substantially along the line 12—12 of Fig. 9.

In all of the above described views like characters of reference are employed to designate like parts throughout.

Referring now to the drawings in detail, and particularly to Figs. 1, 2 and 3, the stenographic machine involves in its general organization a stationary framework designated in its entirety at 10 and including a pair of side plates 12 and 14, a rear plate 16 and a front plate 18. The front plate 18 is provided with an offset portion 20 designed to accommodate certain groups of character keys associated with the keyboard of the machine, as will be described presently. The side plates 12 and 14 and front and rear plates 18 and 16 respectively form a generally rectilinear

open framework within which is situated the operative machine instrumentalities subsequently to be described. This open framework is supported at the four corners thereof by means of angle pieces 22, in the form of short legs or supports, to which both the side plates and the front and rear plates are secured by means of screws 24 and which serve to maintain the stationary framework of the machine elevated from the supporting surface upon which the machine rests. The side plates 12 and 14 are formed with upstanding wing portions 26, one of which appears in Fig. 2.

The keyboard of the machine appears in Fig. 1 and is designated in its entirety at 28. This keyboard, together with numerous modifications thereof, has been shown and described in my above mentioned patent and no claim is made herein to any novelty associated with the particular arrangement of the various keys. For purposes of illustration, it is deemed sufficient to state that the present keyboard arrangement is the result of an exhaustive study of the occurrence of English words, and sequence of letters in the words, that are used most frequently in business, literature and other fields of human activity. The keyboard, as shown herein, includes eleven groups of keys, each group being designated in its entirety at 30 and consisting of three individual keys 32 within the group. A space key or bar 34 is also associated with the keyboard 28. As explained in the patent, the keys are arranged as simply as possible for ease in memorizing the characters thereof and for ease of combination fingering, since writing speed is dependent upon these features. In order that the fingers may readily reach all of the keys with short vertical movement, the keys are arranged in an extremely compact formation. Four of the multi-key groups 30 are disposed at the left side 30 of the machine in the rear regions of the keyboard. Five of these key groups are similarly disposed rearwardly of the keyboard at the right side thereof. The space bar 34 is positioned rearwardly of the keyboard between the two pairs of key groups just described. The remaining two key groups occupy positions forwardly of the keyboard within the space afforded by the offset portion 20 of the front plate 18. The four key groups existing at the left-hand side of the keyboard are capable of being operated by the four fingers of the left hand to produce different initial consonants and consonant-combinations. The four fingers of the right hand are utilized to actuate the five key groups at the right-hand side of the keyboard to produce various final consonants and consonant-combinations, as well as certain punctuation marks. The two thumbs are employed in operating the two key groups at the forward central region of the keyboard to produce whatever vowels or vowel combinations are encountered. The various keys 32 are labeled accordingly, all substantially as shown and described in my above mentioned patent.

Each of the consonant keys 32 (see Figs. 3 and 5) is mounted adjacent the forward end of a horizontally disposed tiltable key lever 36 and each of the vowel keys 32 is mounted adjacent the forward end of a similar but somewhat longer lever 36', there being thirty-four such levers in all to accommodate the thirty-four keys of the keyboard 28. All of these levers are loosely mounted near the rear of the machine on a horizontal supporting shaft 38, the ends of which are anchored to and supported from the side plates

12 and 14 by means of nuts 49 which are threadedly received on the threaded ends of the shaft 38. A series of spacing collars 44 are mounted on the shaft 38 and serve to maintain the rear ends of the levers 36 spaced apart, as shown in Fig. 3.

As explained in my prior patent above referred to, since the various keys 32 of the key groups 30 are arranged in close proximity to each other and in alignment, as shown in Fig. 1, to permit simultaneous striking of adjacent keys by the same finger, the various key levers 36 or 36' extend across the machine from front to rear thereof and are arranged in groups of three levers each with the levers of each group being arranged in close proximity to each other and with a comparatively wider distance between adjacent groups, as shown in Fig. 3. Thus, to accommodate all thirty-three of the alphabetical keys, there are eleven such lever groups in all. The space key or bar 34 is mounted upon an individual lever 37 which is also pivoted for tilting movement to the shaft 38.

A guide bar 46 (see Figs. 3, 5, 8 and 9) is secured in any suitable manner, as for example, by means of screws 48, to the inside of the front plate 18 and is provided with a series of grooves 50 therein which are adapted to slidably receive the forward ends of the various consonant key levers 36, as well as the forward end of the space bar lever 37. The two groups of levers 36 in the central regions of the machine which serve to accommodate the vowel keys 32 arranged within the offset portion 20 of the front plate 18 pass completely through slots 51 formed in the guide bar 46 and the extreme forward ends of these individual bars terminate just short of the forward wall of the offset portion 20. Slots 52 formed in the upper edge of these latter bars, as shown in Fig. 9, permit the bars to assume their normal horizontal position in a plane common to all of the levers 36 and 36'. A limiting strip 54 is secured in any suitable manner, as for example by means of screws 56, to the upper edge of the guide bar 46 to determine the uppermost position of the various consonant key levers 36.

The side plates 12 and 14 are provided with outwardly struck flanges 58 (Figs. 2, 3 and 9) medially of their lower edges, to which flanges there is secured a horizontal bar 60 which extends completely across the machine in the lower regions thereof. A plurality of strips of spring sheet material 62 are secured to the upper side of the bar 60 and each of these strips is provided with a series of rearwardly extending spring fingers 64 having upturned ends 66 designed for engagement with the underneath edge of the various levers 36, 36' and 37. These spring fingers serve to normally bias the levers to their raised or elevated positions. For convenience, there have been provided three such strips 62 in all, two of them accommodating the consonant key levers at the right- and left-hand sides of the levers respectively and the other strip serving to accommodate the two groups of vowel key levers. An individual string strip 63 serves to accommodate the space bar lever 37, as shown in Fig. 8. The various levers 36, 36' and 37 are provided with localized knife-edge regions 68 designed for engagement with the upturned ends 66 of the various spring fingers 64 to reduce friction between the parts to a minimum.

As set forth in my above mentioned patent, the individual consonant and vowel keys 32 associated with each group 30 thereof are adapted to be

selectively depressed singly to print the alphabetical character which they represent. Each pair of adjacent keys within a group is also adapted to be selectively depressed simultaneously, such simultaneous depression thereof serving to print an alphabetical character different from either of the characters which they individually represent. Thus, according to the keyboard shown in Fig. 1, the three keys 32, shown in side elevation in Fig. 5, may represent, reading from left to right, the characters T, S and Q according to the labeling thereon. Depression of any one of these keys singly will cause a corresponding alphabetical character to be printed. If, however, the two adjacent keys representing the letters T and S are simultaneously depressed, the letter D will be printed, as indicated by the labeling. Similarly, if the two adjacent keys S and Q are simultaneously depressed, the letter K will be printed, as shown by the labeling.

Means are provided for preventing subsequent depression of one or more of the keys 32 after individual or simultaneous depression of any of them. For example, if in the keyboard shown in Fig. 1, the key representing the letter N is depressed, all of the remaining keys of the keyboard become locked against depression until such time as the first key has been released. This locking arrangement, however, does not preclude simultaneous depression of more than one key at a time. Yet, after such simultaneous depression of keys has taken place, further depression of the keys, either individually or in pairs, is prevented. Toward these ends, a horizontal rock shaft 70 extends transversely across the machine and is journaled in any suitable manner in the two side plates 12 and 14 thereof for limited oscillating movement. A plurality of locking elements 72 are mounted upon and keyed to the rock shaft 70 for oscillation in unison therewith. The elements 72 are suitably spaced from each other on the shaft 70 and each is in the form of a flat sheet or strip stock having an irregularly shaped slot 74 formed therein, thus providing two generally parallel, substantially radially extending arms 76 and 78. A plurality of coil springs 80 suitably secured to a rod 82 extending between the side plates 12 and 14 are anchored to certain of the members 72 and exert their influence to maintain the rock shaft 70 in one extreme position. The arm 76 of each member 72 is slightly longer than the arm 78 and, by virtue of the nature of the slot 74 existing between the two arms, is provided with an inclined cam portion 84 thereon. The upper end of each arm 76 normally bears against a pin 86 mounted at one side of one of the levers 36, it being understood that for each of the levers 36 there is a corresponding locking element 72. The upper portion of each of the arms 78 is turned laterally as at 88 and its extreme upper end constitutes an abutment for the pins 86. From the above description of parts, it will be seen that upon depression of any one of the keys 32 in the entire keyboard, the pin 86 attached to the lever 36 associated with that key will be lowered into the slot 74 of the corresponding locking member 72. As the pin 86 rides downwardly on the cam surface 84, the locking member 72, together with the shaft 70 upon which it is mounted, will be tilted to a slight extent in a clockwise direction, as shown in Fig. 5, thus moving with it all of the other locking members 72 which control the functioning of the various other keys 32 with which they are associated. When all of the locking members 72 have been thus tilt-

ed in a clockwise direction, the extreme upper end of the arms 78 of each locking member 72, with the exception of the locking member associated with the depressed key, will underlie the respective pins 86 to prevent further depression of any of the levers 36. By such an arrangement it is possible to depress more than one key at a time, provided the depression of the keys is made substantially simultaneously. In such an instance, all of the pins 86 associated with the simultaneously depressed keys will ride into their respective slots 74 and the rock shaft 70 will be tilted in a clockwise direction, as heretofore described. After the pins 86 have arrived at the bottom of the slots 74 of the corresponding members 72, the entire locking assembly will have been shifted to such a position that no further depression of keys is attainable.

Referring now to Figs. 3, 7 and 9, the type bars 90, of which there are eleven in number, are arranged in a line along the printing line of the platen 92 and are adapted to move bodily in substantially straight linear, or very slightly curved, paths to and from the printing point to engage the platen or a strip of work tape passed there-around. Each of the type bars carries five types designated at *k*, *d*, *s*, *q* and *t*, arranged in vertical alignment on the front surface of the various type bars 90, this latter surface being arcuate in form so that each type will engage the platen with the same degree of pressure. Each of the type bars 90 is operable by one of the groups 32 of three keys each associated with the keyboard and the type bars are adapted to assume any one of five different printing positions, depending upon the manner in which the three keys of the group are depressed. Accordingly, each of the type bars 90 operates under the control of a suitable toggle linkage mechanism, designated in its entirety at 94, which is controlled by means of three depressable key levers 36 associated with the particular group of keys concerned. The toggle linkage mechanism 94 operates both to impart the desired degree of angularity to the type bar 90 as well as to cause linear movement of the latter for printing purposes, all under the influence of a permutation system of leverage, the nature of which will be described presently. The various toggle linkage mechanisms 94 associated with the consonant keys are substantially identical in their construction and, consequently, it is thought that a description of one of these linkages will suffice for them all. A slightly modified, yet somewhat similar, toggle linkage mechanism is employed for controlling the two type bars that are operated under the control of the two groups of vowel keys. This modified linkage system will be described at a later point in this specification.

A pair of spaced supporting plates 100 extend across the framework from the front to the rear thereof and each is provided with an upstanding portion 102 (Figs. 8 and 9) having laterally turned flanges 104. Similar laterally turned flanges 106 formed on the side plates 12 and 14 serve in conjunction with the flanges 104 to support thereon a transverse angle piece 108. The angle piece 108, in addition to serving its function as a transverse support for the machine framework, also serves as an anchoring member for a plurality of springs 110 associated with the various linkage mechanisms 94, as will appear presently. A shaft 114 extending between the two plates 100 near the top thereof serves as a suspension rod for a plurality of downwardly depending bifurcated suspension links 116. The 75

various type bars 90 are each pivotally connected as at 118 medially to a respective link 116. A support 95 spans the distance between the two plates 100 and carries a strip of spring material 96 having spring fingers 97 formed thereon, these latter fingers serving as stops to limit the upward movement of the type bars 90.

Thus far, the description for the type bars 90 and their controlling mechanism is substantially the same in the case of the nine consonant type bars as for the two vowel type bars. In the case of the consonant type bars, each of the suspension links 116 is pivotally connected as at 120 to a thrust link 122, the other end of this latter link being pivotally connected as at 124 to a swinging link 126 medially thereof. The lower end of the link 126 is tiltably supported upon a cross rod 128 which extends completely across the machine transversely thereof, passes through the two spaced supporting plates 100 and has its ends anchored to the side plates 12 and 14. Each of the links 126 is curved rearwardly as at 130 and has attached to its rearmost end an L-shaped link 132 (see also Fig. 3). The various L-shaped links 132, when in their normal positions, are nested together one within the other, as shown in Fig. 3. The four links 132, associated with the four groups of consonant keys at the left-hand side of the machine, extend laterally to the left, as shown in Fig. 3, in nested relationship, while the five links 132 associated with the five groups of consonant keys at the righthand side of the machine extend to the right in nested fashion, as shown in Fig. 3, and thus there are nine such nested links 132 in all. Each of the links 132 is provided with a horizontal arm 134, the inner end of which is attached to its respective link 126. The respective lengths of the various horizontal arms 134 differ, of course, since the various groups of consonant keys occupy different lateral positions along the keyboard. The links associated with the two extreme right- and left-hand groups of keys have the longest horizontal arms and the links associated with the two innermost right- and left-hand groups of consonant keys have the shortest horizontal arms. Each of the links 132 is provided with an arm 136 designed for limited swinging movement in a vertical plane about the axis of the rod 128. Each arm 136 is provided with a lateral extension 138 which, in combination with the arm 136, forms in effect a bell crank lever having a particular function in the linkage system, as will appear presently. The outer end of the laterally extending arm 136 is pivoted as at 140 to a substantially vertically disposed link 142, the lower end of which carries a horizontally disposed thrust pin 144 of sufficient length to span the three depressable key levers 36 in the particular group of levers with which it is associated. Each of the pins 144 underlies the three depressable key levers 36 of the group with which it is associated and is adapted to ride in a series of slots 146 of equal extent which are formed in the levers.

The linkage system thus far described is primarily adapted for use in imparting longitudinal printing thrust motion to the type bar 90. This component of motion applied to the type bar remains substantially the same regardless of the angular position thereof. The angular position of the type bar is controlled by a different but interrelated system of linkages that will next be set forth. It will be noted that upon depression of any one or more of the three consonant keys 32 in

a group 30 thereof, a linkage motion will be set into effect which is caused by lowering of the pin 144 and link 142, counter-clockwise tilting of the bell crank lever 138, 136, as viewed in Fig. 5, similar counterclockwise tilting motion of the link 126 attached to the bell crank lever, forward movement of the link 122, swinging movement of the suspension link 116 in a clockwise direction and consequent forward, substantially linear movement of the type bar 90.

The angular tilting movement of the type bar 90 to bring a selected type *k*, *d*, *s*, *q* or *t* into alignment with the printing point on the platen is effected by means of a link 150, the upper end of which is pivotally connected at 152 medially of the type bar 90 and the lower end of which is pivotally connected as at 154 to an inclined bar 156. Each of the bars 156 is provided with a forward, relatively long portion 158, pivoted adjacent its forward region to the rod 128, an inclined, transversely disposed portion 160 and a relatively short forward inclined offset portion 162. This latter portion has secured thereto in any suitable manner, as for example, by means of rivets 164, a U-shaped permutation link 166 having a substantially horizontal base portion 168 and an upstanding arm 170 pivotally connected to the rod 128. It is to be noted that the bar 156, together with its offset portion 162 and the U-shaped link 166, forms a substantially rigid structure which is designed for limited rocking movement about the axis of the rod 128. The extreme upper end of the arm 170 is provided with a hole 172 affording attaching means for the various springs 110 which are anchored to the angle piece 108. In this manner, the rigid linkage structure just described is operatively biased for tilting movement about the axis of the rod 128 in a clockwise direction.

Referring now to Figs. 5, 6 and 7, each of the U-shaped permutation links 166 is designed for cooperation with a respective group of closely spaced key levers 36 and, depending upon which lever or levers of the group thereon are depressed, the link is adapted to assume any one of five different angular positions to cause the type bar 90 to selectively present one of the types *k*, *d*, *s*, *q* or *t* to the printing point of the platen. The base portion of the U-shaped permutation link 166 has pivoted thereto at a point 174 a relatively short cross head 176. Each end of the cross head carries a pivoted leg, which legs are designated at 178 and 180 respectively. The legs 178 and 180 depend downwardly from the cross head 176 and are provided with foot portions 182 adapted to be received in a plurality of aligned permutation slots formed in the upper edges of the three levers 36. The nature of the slots, which are formed in the levers 36 and which receive the foot 182 of the leg 180, is clearly shown in Fig. 6 and is diagrammatically represented in Fig. 7. The nature of the slots which receive the foot 182 of the leg 178 is also diagrammatically represented in Fig. 7.

As previously set forth, the three keys 32 of Fig. 5 have been labeled T, S and Q, according to the characters which they represent, with intermediate characters D and K illustrating combinational characters when two adjacent keys are depressed. The same labeling has been applied to the levers 36 in Figs. 6 and 7 to facilitate the ensuing description. The center or S-lever 36 is provided with a relatively shallow slot 184, while the T- and Q-levers are provided with somewhat deeper slots 186 and 188. These slots

are in transverse alignment and when the foot 182 of the leg 180 is received therein it will occupy an elevated position with its lower edge resting upon the bottom of the shallow slot 184, as shown in Fig. 6. The three levers 36 are also provided with additional slots 190 in the case of the S-lever, 192 in the case of the T-lever, and 194 in the case of the Q-lever. These slots also are in alignment. The slot 190 is of rectilinear configuration and is relatively deep. The slot 192 is generally V-shaped, is fully as deep as the slot 190 and is provided with a side 196 which is inclined in one direction. The slot 194 is also generally of V-shape but is shallower than either the slot 190 or 192 and is provided with a side 198 which is inclined in a direction opposite to the direction of the side 196 of the slot 192. When the three levers 36 are in their elevated positions with their outer upper edges bearing against the strip 54, the three slots 190, 192 and 194 take on the aspect illustrated in Fig. 5 with the foot 182 of the leg 178 resting upon the two inclined sides 196 and 198 of the slots 192 and 194 respectively and elevated a substantial distance above the bottom of the slot 190.

With the three levers 36 in their elevated position and the two feet 182 occupying the position shown in Fig. 5, the cross head 176 assumes a substantially horizontal position and the U-shaped permutation link 166 assumes a normal position wherein the type bar 90 is swung downwardly about the pivotal point 118 and wherein none of the type elements *k*, *d*, *s*, *q* or *t* is in register with the printing point on the platen 92. 35 When the T-lever is depressed, this lever drops below the level of the S- and Q-levers and in such an instance the level of the foot 182 of the leg 180 is not altered, inasmuch as it rests upon the bottom of the slot 184 in the S-lever, the elevation of which is not disturbed. However, upon such depression of the T-lever, the inclined side 196 of the permutation slot 192 is withdrawn from its supporting position and the foot 182 of the leg 178 slides downwardly on the inclined side 198, thus allowing the cross head 176 to become tilted slightly to the left, as viewed in Fig. 5. The pivotal point 174 of the cross head 176 may be considered as an operating point, the elevation of which determines the angular position of the type bar 90. Thus, when the cross head 176 becomes tilted, as just described, this operating point is lowered a slight degree and its lowering effect is magnified through the linkage system, including the bar 156 and link 50 150 so that the type bar 90 is swung upwardly to a position wherein the type *t* becomes aligned with the printing point on the platen 92. As the T-lever is moved further toward its final position, the linkage system including the swinging link 126 and thrust link 122 and suspension link 116 is set into operation to move the type bar 90 substantially linearly and effect the printing operation utilizing the type *t*.

Upon depression of the Q-lever, the elevation 65 of the foot 182 of the leg 180 is not disturbed, inasmuch as this foot still rests upon the bottom of the slot 184 of the S-lever. However, such depression of the Q-lever serves to withdraw the inclined support 198 afforded by the slot 194 70 for the foot 182 of the leg 178 and this foot is caused to slide downwardly on the inclined support 196 until it reaches the level of the bottom of the slot 190. This level being somewhat lower than the level encountered during the printing 75 of the type *t*, the cross head 176 becomes inclined

to the left to an extent sufficient to swing the type bar 90 upwardly and cause the type *q* to move into register with the printing point on the platen 92. As in the case of the type *q*, complete depression of the Q-lever also imparts linear printing movement to the type bar 90.

Upon depression of the S-lever the bottom of the slot 190 is lowered away from the foot 182 of the leg 178, but this foot continues to obtain a support on the two inclined surfaces 196 and 198. However, when the S-lever is depressed, the bottom of the shallow slot 184 is lowered so that the foot 182 of the leg 180 moves downwardly, thus lowering the operating point 174 to a degree sufficient to swing the type bar 90 upwardly until the type *s* becomes aligned with the printing point on the platen 92. The linear printing operation takes place as described heretofore.

When the adjacent T- and S-levers are simultaneously depressed, the initial support of the foot 182 for the leg 180 is lowered, while at the same time the inclined surface 196 of the slot 192 is withdrawn from beneath the foot 182 of the leg 178. Thus, this foot 182 will move downwardly on the inclined surface 198, as previously described, and the operating point 174 of the cross head 176 and link 166 will be lowered to an extent greater than any previously described. In such an instance, the type bar 90 will be swung upwardly until the type *d* falls into register with the printing point on the platen 92. Linear printing takes place as usual.

Upon simultaneous depression of the S- and Q-levers all initial support for both of the feet 182 is removed. In such an instance, both of these feet are lowered to the fullest extent permitted by the permutation slots and the operating point 174 is moved to its lowermost limiting position so that the type bar 90 is fully elevated with the type *k* in register with the printing point on the platen 92.

Simultaneous depression of the T- and Q-levers or of the T-, S- and Q-levers is possible and in such an instance, since all initial support for the two feet 182 would be withdrawn, the type bar 90 would print the character *k*. However, such depression of non-adjacent keys or of the three keys in a group is not contemplated according to the present system of stenography.

At this point it will be apparent that the previously described locking member 72, by serving to prevent depression of any other key after a first key or pair of keys has been depressed, will preclude the possibility of printing until one or another of the various types *k*, *d*, *s*, *q* or *t* is definitely in register with the printing point on the platen 92 for printing purposes.

The controlling mechanism for the two type bars 90 which carry vowel characters operates upon the same principle as the controlling instrumentalities for the nine type bars which carry consonant characters. However, since the vowel key levers are situated centrally of the machine and are longer than the other consonant key levers, the angular inclined bars 156 and the U-shaped permutation links 166 may be dispensed with and a simplified permutation system substituted in their stead. Such a simplified structure is shown in Figs. 4 and 9. Referring now to these figures, the type bars 90, suspension links 146, thrust links 122 and elevating link 150 remain substantially the same as heretofore described.

The means for applying lateral thrust to each

of the vowel type bars 90 is embodied in a linkage system including a substantially vertically disposed link 200 similar to the link 142. The lower end of the link carries a pin 202 similar in function to the pin 144 and this latter pin cooperates with a series of notches 204 formed in the underneath sides of the three key levers 36. The upper end of the link 200 is pivotally connected as at 206 to an inclined arm 208 formed on a tiltable U-shaped link 210. The section line 9—9 of Fig. 3 passes medially through one of the U-shaped links 210, and, as a consequence, the inclined arm 208, shown in Fig. 9, is not a part of the U-shaped link 210 but is a part of the next adjacent link. Since there are two vowel type bars 90, there are two links 210. One-half of each link is shown in Fig. 9 and these two links are similar in design but are complementary in form, one accommodating the left-hand vowel type bar, and the other accommodating the right-hand vowel type bar. Each U-shaped link 210 is provided with a second arm 212, the upper end of which is pivoted to the thrust link 122. From the above description, it will be seen that upon depression of any one of the three key levers 36 a linkage system passing through links 200, 210, 122 and 116 will operate to move the type bar 90 linearly, as previously described. The angular tilting movement of each of the two vowel type bars 90 to bring a selected type *i*, *u*, *e*, *o*, or *a* into alignment with the printing point on the platen is effected by means of a permutation bar 214 which occupies a substantially horizontal position in the machine and which is generally of U-shaped design, including a long arm 216 pivoted at 154 to the lower end of the link 150 and a short arm 218, the end of which is pivotally connected to a shaft 200 that extends between the two upstanding frame portions 102 near the forward edge thereof. The shaft 200 also passes through the long arm 216.

Referring now to Fig. 9, a cross head and leg arrangement substantially identical with the cross head and leg arrangement 176, 180, 182, etc., of Fig. 5, and similarly designated, is pivotally secured at 174 to the inner side of the short arm 218 of the permutation link 214 and the foot portions 182 thereof cooperate with a series of slots 184, 186, 188, 190, 192 and 194 identical in design and function with the similarly numbered slots of Fig. 5 to effect different angular positions of the permutation bar 214 and elevate the type bar 90 accordingly to selectively present the types *i*, *u*, *e*, *o* or *a* to the printing point of the platen, as previously described.

The keys 32 of Fig. 9 are vowel keys and they have been labeled, reading from left to right, *I*, *E*, *U* in a manner similar to the labeling of the keys 32 of Fig. 5. The vowel characters *O* and *A* appearing in this figure represent intermediate combinational characters similar to the consonant characters *D* and *K*. Thus, upon simultaneous depression of the *I* key and the *E* key, the type bar 90 will be elevated to such a position that the type *o* moves into register with the printing point of the platen. Similarly, upon simultaneous depression of the *e* key and the *u* key, the type bar 90 will be elevated so that the type *a* falls into register with the printing point of the platen.

It is to be noted that locking elements 72 which are identical with those previously described are operatively mounted on the shaft 70 and cooperate with the two groups of vowel key levers. Since the locking members 72 are mounted on the rotatable shaft 70, the locking

action obtains for the entire keyboard whether consonant or vowel characters are concerned. The paper feeding mechanism and the ribbon feeding mechanism are related to each other to the extent that they are both actuated from a common depressable actuating 235. The paper feed instrumentalities are under the control of a ratchet and rack mechanism which is operated through a linkage system controlled by the bar 235, while the ribbon feed mechanism operates under the control of a ratchet and pawl mechanism operating through a linkage mechanism also controlled by the bar 235.

The paper feed mechanism is best illustrated in Figs. 3, 8, 9 and 11. The machine employs an elongated strip of conventional stenographic or adding machine type of tape T which is supplied in the form of packets consisting of continuous folded layers of material, as shown near the bottom of Figs. 9 and 11. This paper stock is adapted to be received in a narrow elongated chamber 250 afforded by a container 252 which may be formed of sheet metal and which is situated on the underneath side of the machine and suitably anchored to the spaced supporting plates 100 in any suitable manner, as for example, by means of fastening screws 254. The container 252 is provided with an extensible, open-ended tray 256 which is slidable thereon and which may be pulled outwardly to underlie and project rearwardly of the platen 92 for the purpose of receiving therein the continuous stock which has been operated upon by the printing mechanism. The use of such a storage compartment, and of an extensible stock receiving tray therefor, is old and no claim is made herein to any novelty associated with the same.

The platen 92 is rotatably supported between two side plates 258 (Figs. 8 and 9) which are anchored by means of fastening screws 260 to the supporting plates 100 at the rear of the machine. The platen includes the usual rubber or other composition platen roller 262, a ratchet wheel 264 at one side thereof and a finger knob 266 at the other side thereof for manual manipulation of the platen. A keeper bracket 268 is pivotally mounted on a shaft 270 extending between the two side plates 258 and carries a roller 272 designed for cooperation with the platen roller 262. A spring 274 serves to bias the keeper bracket 268 and effect cooperation between the keeper roller 272 and the platen roller 262. Paper issuing from the chamber 250 is passed upwardly around a roller 276, over and above a curved plate 278 mounted on the shaft 270 extending between the two side plates 258, around the platen roller 262 and between this roller and the roller 272, and finally downwardly into the tray 256.

The previously mentioned depressable bar 235 is carried at the free ends of a pair of arms 282 (Fig. 5) mounted upon and movable with a rock shaft 284 extending across the machine and the ends of which are rotatably journaled in the side plates 12 and 14. A spring 286 surrounding the shaft 284 bears at one end against the underneath side of the bar 68 and at the other end against the underneath edge of one of the arms 282 to normally urge this arm, and consequently the bar 235, to its uppermost position in close proximity to the underneath edges of the various key levers 36, 36'. A series of resilient sleeves 288, which may be formed of rubber or other resilient material, are mounted on the bar 235 and are designed for direct contact with the underneath edges of the key levers 36 in order that when one or more of these latter levers are depressed the bar 235 will

be moved downwardly, thus swinging the arms 282 in a clockwise direction, as viewed in Fig. 5. Such downward movement of the bar 235 operates through linkage mechanism, about to be described, to index the ribbon and also to preset the platen indexing mechanism for subsequent indexing action when the key levers are released and the bar 235 again is restored to its normal upper position.

10 Referring now to Figs. 8, 9 and 11, an operating lever 290 is pivoted as at 291 to each of the spaced supporting plates 100. The two levers 290 project forwardly of the machine and are provided with bifurcated ends 292 which straddle the bar 235, as shown in Fig. 8. The lever 290 is pivotally connected as at 294 to a link 296, which is in turn connected by a pin and slot connection 298 to an irregular angular shaped lever 300. The lever 300 is pivotally mounted on a shaft 302 supported between the side plates 100 and is provided with a laterally turned portion 304 having a laterally extending offset ear 306 (Fig. 9) also pivoted to the shaft 302. The lateral extension 304 and ear 306 are provided for the purpose of offering rigidity of mounting to the lever 300. The lever 300 is pivotally connected as at 308 to one end of the thrust link 310, the other end of the link being pivotally connected as at 312 to an angular pawl piece 314, which is in turn pivotally mounted on the shaft 38 and biased in one direction by means of a spring 315. The pawl piece 314 carries a stud 316 on which there is pivoted a rack 318 designed for cooperation with the teeth provided on the platen ratchet wheel 264. A small spring 320 is anchored at one end to the body portion of the pawl piece 314 and at the other end to an offset lug 322 formed on the rack member 318. In order that the teeth of the rack shall at all times be maintained in operative engagement with the teeth on the platen ratchet wheel, a holding pawl 324 is pivoted as at 326 to the side plates 258 and is spring-pressed as at 328 into engagement with the teeth on the platen ratchet wheel to prevent reverse movement of the latter.

45 As previously stated, the operating mechanism for the platen 92 is of the presetting type. In other words, initial actuation of the mechanism serves to preset the rack 318 against the action of the spring 320. Upon releasing of the mechanism, the rack is left free to perform its operative stroke under the influence of the spring 320.

50 The ribbon supporting and feeding mechanism is best illustrated in Figs. 3, 8, 9 and 11. The ribbon is carried upon two spools 301 and 303 which are removably mounted upon and keyed to a pair of sleeves 305 rotatably disposed upon stub shafts 307 anchored to the side plates 100. Securing nuts 309 are provided for holding the spools in position on the sleeves 305. Each of 55 the sleeves 305 has mounted thereon a gear 311 adapted to be alternately driven by the ribbon advancing mechanism, the nature of which will be set forth presently. The metal of the upwardly extending portion 102 of the side pieces 100 is struck outwardly as at 313 to provide a pair of ribbon guides and a ribbon R is adapted to pass over these guides and between the type bars 90 and platen 92 in passing from one ribbon spool to the other.

60 70 Each of the levers 290 is provided with an offset portion 330, to which there is pivoted the forward end of a link 332, the rear end of this link being pivotally attached to the lower end of an arm 334, which arms are integrally formed on a tiltable bracket 336 (see Fig. 9). The

bracket 336 carries a pair of ears 338 across which there extends a short shaft 340 carrying a pawl 342 designed for indexing engagement with a ratchet wheel 344 centrally mounted on a shaft 346 suspended across the upper ends of an oscillatable U-shaped bracket 348 which is pivoted as at 350 on a plate 352 secured by means of attachment lugs 353 to the sides of the upstanding plates 100.

Referring now to Figs. 3 and 11, the shaft 346 has mounted thereon a pair of pinions 354 and 356, the former being designed for cooperation with the gear 311 associated with the spool 301. The pinion 356 is designed for cooperation with the gear 311 which is associated with the spool 303. When the bracket 348 occupies one position of angularity, as shown in Fig. 3, the pinion 354 is maintained in mesh with its respective gear 311. Similarly, when the bracket 348 assumes its other position of angularity, the pinion 356 is designed for cooperation with its respective gear 311.

Referring now to Fig. 11, the bracket 348 is spring biased and is adapted to be moved over a dead-center to either of its extreme limiting inclined positions. Toward this end, the bracket 348 is provided with an elongated arm 358, the outer end of which carries a lug 359. The arm 358 projects beyond the front edge of the plate 352 and a bowed spring 360 at one end thereof is secured in a slot 362 formed in the lug 359 and the other end thereof is secured in a slot 364 provided in the forward edge of the plate 352. The bracket 348 thus possesses a degree of unstable equilibrium and is normally urged to either of its extreme positions to cause one or the other of the two pinions 354 or 356 to move into engagement with its respective gear 311. It is to be noted at this point that regardless of which position the bracket 348 assumes, the extent of change in its angularity with respect to the pawl 342 is not so great as to prevent proper functioning of this latter part.

A holding pawl 363 is pivoted to a pair of ears 366 formed on the plate 352 and operates under the influence of gravity to prevent retraction of the ratchet wheel 344. The tiltable rotatable shaft 346 carries adjacent its opposite ends a pair of eccentric cam members 368 which are so positioned as to bear against respective rolls of ribbon material mounted on the spools 301 and 303. During ribbon feeding operations under the influence of the ratchet and pawl mechanism 342, 344, the particular cam member 368 associated with the ribbon spool which is undergoing indexing, is adapted to bear against the ribbon material as it rotates. This will cause the shaft 346 to be repeatedly oscillated throughout small accurate degrees with the shaft gradually approaching its dead-center position. When this dead-center position is attained and extended, by virtue of the ribbon material building up on the spool, the bracket will be automatically carried over the dead-center position by the spring 360, thus causing disengagement of one of the pinions 354 or 356, as the case may be, with its respective gear 311 and engagement of the other pinion with its respective gear to condition the ribbon for reverse indexing.

Referring now to Figs. 3 and 8, the space key 34 is suitably mounted on the space bar 37 adjacent the forward edge of the latter. This space bar 37 is pivoted on the shaft 38. The function of the space key is to index the platen roller two spaces upon a single depression of the space

key as distinguished from the single spacing operation of any of the character keys. The space key 34 is preferably positioned well within the confines of the keyboard and just inside the left-hand group of consonant keys 36. The lever 300 associated with the platen indexing linkage system is provided with a laterally extending arm 372, the free end of which underlies the space bar 37, as shown in Fig. 8. Upon depression of the space key 34, the underneath edge of the space bar 37 is adapted to engage the arm 372 to rock the lever 300 in a counter-clockwise direction, thus causing indexing of the platen 92 in a manner that has previously been described in connection with the linkage system which controls the platen indexing operation. The extent of the arm 372 with respect to the point of pivotal connection for the lever 300 and its relation to the space bar 37 is so calculated in accordance with engineering practice that upon full depression of the space bar 37 the lever 300 will be tilted to the proper extent in order that the rack and ratchet assembly which controls the operation of the platen will be actuated to an extent sufficient to cause double spacing of the record media associated with the platen.

The invention is not to be limited to the exact arrangement of parts shown in the accompanying drawings or described in this specification as various changes in the details of construction may be resorted to without departing from the spirit of the invention. Only insofar as the invention has been particularly pointed out in the accompanying claims is the same to be limited.

35 What is claimed is:

1. In a printing shorthand machine including a printing platen, a type action comprising a tiltable bodily movable type bar, a plurality of type thereon, depressable key levers associated with said type bar and of a number less than the number of type thereon, operating means common to all of said levers for tilting said type bar to bring a selected type thereon into register with the printing point on said platen, said operating means comprising a linkage system including a permutation member capable of assuming different positions commensurate with the inclination of said type bar, supporting means formed on said levers for supporting and maintaining said permutation member in its various positions depending upon the relative positions of said levers with respect to each other, and means normally and yieldingly urging said permutation member into engagement with said levers.

2. In a printing shorthand machine including a printing platen, a type action comprising a tiltable bodily movable type bar, a plurality of type thereon, depressable key levers associated with said type bar and of a number less than the number of type thereon, operating means common to all of said levers for tilting said type bar to bring a selected type thereon into register with the printing point on said platen, said operating means comprising a linkage system including a permutation member capable of assuming different degrees of elevation commensurate with the inclination of said type bar, and a supporting foot for said permutation member adapted to bear against and rest upon said key levers and to assume different elevational positions upon selective depression of the latter, there being a plurality of aligned notches formed in said levers of varying depth and into which said supporting foot extends.

3. In a printing shorthand machine including

a printing platen, a type action comprising a tiltable bodily movable type bar, a plurality of type thereon, depressable key levers associated with said type bar and of a number less than the number of type thereon, operating means common to all of said levers for tilting said type bar to bring a selected type thereon into register with the printing point on said platen, said operating means comprising a linkage system including a permutation member capable of assuming different elevational positions commensurate with the inclination of said type bar, a cross head pivotally mounted on said permutation member at an operating point thereon, and a pair of supporting legs depending from said cross head on opposite sides of the operating point and adapted to bear against said key levers, each of said supporting legs assuming different elevational positions upon selective depression of the key levers, there being a plurality of notches formed in said levers for reception therein of said supporting legs.

4. In a printing shorthand machine including a printing platen, a type action comprising a tiltable bodily movable type bar, a plurality of type thereon, a pair of depressable key levers associated with said type bar, operating means common to both of said levers for tilting said type bar to bring a selected type thereon into register with the printing point on said platen, said operating means comprising a linkage system including a permutation member capable of assuming different elevational positions commensurate with the inclination of said type bar, means formed on said levers for selectively supporting said permutation member in its various elevational positions depending upon selective depression of said levers, and means normally urging said permutation member into supporting engagement with said levers.

5. In a printing shorthand machine including a printing platen, a type action comprising a tiltable bodily movable type bar, a plurality of type thereon, a pair of depressable key levers associated with said type bar, operating means common to both of said levers for tilting said type bar to bring a selected type thereon into register with the printing point on said platen, said operating means comprising a linkage system including a permutation member capable of assuming different elevational positions commensurate with the inclination of said type bar, means formed on one of said levers for supporting said permutation member in an elevated position when said lever remains elevated and means formed on the other key lever for supporting said permutation member in a lower elevational position when said first lever is depressed and when said last mentioned lever remains elevated.

6. In a printing shorthand machine including a printing platen, a type action comprising a tiltable bodily movable type bar, a plurality of type thereon, depressable key levers associated with said type bar and of a number less than the num-

ber of type thereon, operating means common to all of said levers for tilting said type bar to bring a selected type thereon into register with the printing point on said platen, said operating means comprising a linkage system including a permutation member capable of assuming different positions commensurate with the inclination of said type bar, a cross head pivotally mounted on said permutation member at an operating point thereon, a pair of supporting legs depending from said cross head on opposite sides of the operating point, and means on said key levers for supporting each leg in different elevational positions depending upon the relative positions of said levers with respect to each other whereby the elevation of said operating point is altered and the over-all elevation of said permutation member is shifted to cause selective shifting of said type bar.

7. In a printing shorthand machine including a printing platen, a type action comprising a tiltable bodily movable type bar, a plurality of type thereon, depressable key levers associated with said type bar and of a number less than the number of type thereon, operating means common to all of said levers for tilting said type bar to bring a selected type thereon into register with the printing line of said platen, said operating means comprising a linkage system including a permutation member capable of assuming different degrees of elevation commensurate with the inclination of said type bar, supporting means formed on said levers for supporting and maintaining said permutation member in its various positions depending upon the relative positions of said levers with respect to each other, means normally and yieldingly urging said permutation member into engagement with said levers and a second linkage system for moving said type bar bodily toward and away from said printing platen, said linkage system being connected to the type bar and designed for selective engagement with said key levers.
